United States Patent Office

Des. 180,401
Patented June 4, 1957

180,401

CIGARETTE LIGHTER

Robert J. Harper, Scarsdale, and Robert H. Ensign,
Bronxville, N. Y.

Application September 28, 1956, Serial No. 43,138

Term of patent 14 years

(Cl. D48—27)

Fig. 1

Fig. 2

Fig. 3

Fig. 4

Fig. 1 is a side elevation of a cigarette lighter incorporating the design of the present invention and the reverse side of which corresponds with the side shown.

Fig. 2 is a further side elevation corresponding generally to Fig. 1 but showing the cover of the cigarette lighter in open position;

Fig. 3 is a right hand elevation corresponding to Fig. 1; and

Fig. 4 is a top plan view corresponding to Fig. 1. As indicated in the accompanying drawing, the lower portion of applicants' design is transparent.

We claim:

The ornamental design for a cigarette lighter, as shown and described.
